Mount Vernon, N. Y.

Application December 7, 1944, Serial No. 567,020

9 Claims. (Cl. 46—36)

This invention relates to a mechanism for mechanical toy, of the card variety.

In the making of animated cards, that is cards having moving parts, such as are often assembled in books or the like, it is frequently desirable to provide a rotating part. The present constructions, however, for that purpose are not satisfactory. Some of these constructions are so expensive as unduly to increase the cost, and some are incapable of effecting a real rotation of the part, but are limited to an oscillation thereof through a small angle.

It is an object of this invention to provide a construction whereby such a rotation may be performed with a minimum number of parts and with simplicity of construction, but which nevertheless will be capable of giving as complete a rotation of the rotating element as may be desired and which will operate smoothly without binding.

Fig. 1 is a front view of a device embodying this invention in the form of a propeller of an airplane or the like. Fig. 2 is a view of the sheet from which the rack member is formed. Fig. 3 is a section on the line 3—3 of Fig. 2 showing the manner in which the sheet is folded, to form the rack member. Fig. 4 is a detail of the punchings of the front sheet of the device. Fig. 5 is a plan view of the gear. Fig. 6 is a plan view of the propeller. Fig. 7 is a front elevation of a modification of the device embodied in the form of a paddle-wheel partly emersed in water. Fig. 8 is a plan of the member from which the rack is formed for this modification. Fig. 9 shows the way in which the member is folded, to form the rack. Fig. 10 is a fragmentary view showing the manner in which the front card is cut. Fig. 11 is a plan of the gear member used in this modification.

In accordance with this invention, there is provided a card 10 upon which there may be depicted some device, as for example, an airplane not here shown, and in the proper location thereon there is mounted a propeller 11. The construction of this invention provides the mechanism by which this propeller is mounted for rotation and by which its rotation can be achieved, in order to give verisimilitude to the device depicted.

This propeller, as shown in Fig. 6, is stamped from a sheet of cardboard or the like with three propeller blades 12 equally spaced round its center, and extended radially outwardly between each pair of propeller blades is a tab 13. The gear 14 which is also stamped from a sheet of

cardboard or the like has teeth 15 spaced around its periphery like a mechanical gear, and it has a number of slits 16 corresponding to the number of tabs, concentrically spaced around and disposed as shown here at angles of 120 degrees from each other, to receive the tabs 13, when the tabs 13 are bent at right angles to the plane of the propeller. The sheet 10 is provided with an opening 17 of a size to fit snugly over the tabs 13 when bent at right angles to the plane. These tabs thus substantially form a part of a cylindrical surface and serve as a bearing rotating in the said opening.

In assembling the device, the tabs 13 are bent as specified, and are extended through the opening 17, then the slits 16 of gear 14 are fitted over the ends of the tabs 13 on the far side of the paper and the ends are bent out, as shown in Fig. 2, at 18. Thus, the gear and the propeller form an element when connected which may be rotated within the opening 17 with the tabs 13 constituting the shaft.

The rack member comprises a sheet 20 having a plurality of openings 21 arranged on a line 22 parallel to the edge of the sheet, such size and spacing that when the sheet is folded along the line 22, the teeth 15 of the gear 14 may successfully pass through the openings 21 shown in Fig. 2. In assembling this part, the sheet is folded along the line 22 and slipped over one of the teeth 15 and laid flat against the sheet 10. In this position, the sheet 20 is in position to serve as a rack meshing with the gear 14. It is necessary, however, that the parts be held together while the rack is moved longitudinally so as to keep the parts in mesh. Any method of holding the parts in engagement to permit straight line motion of the rack may be employed, for example, we may cut from the body of the sheet 10, C-shaped openings 24 and we may cut from the sheet 20 longitudinal slots 25. Thereupon, the center of the C-shaped tabs may be folded up, and inserted through the slots 25 thereby substantially confining the sheet 20 to a sliding motion parallel to the slots and thereby holding the openings 21 in mesh with the gear teeth.

Ordinarily, we prefer to fold the sheet 20 with the short end 26 folded down between the body 27, of the member 20 and the sheet 10, so that the folded portion 26 is held down by pressure of gear 14 against the sheet 10. This construction makes it possible for the body 27 to overlie the projecting portion of the tabs 13 after they have passed thru the gear 14 and have been bent outwardly as described.

In the modification in Fig. 7, the rotating part comprises a paddle-wheel 40 of a boat or the like pivoted in an opening 41 in the sheet 10 and having its lower edge extending through a slit 42 in that sheet. The opening 41 and slit 42 being spaced with each other in such position that the lower edge of the paddle-wheel 40 will be concealed as though it was rotating under water. In this embodiment, the shaft upon which the paddle-wheel 40 rotates is formed by two slots 43, each having substantially radial edges 44 connected by a concentric curve 45. These slots are bent up and concave sufficiently to cause them to pass through the opening 41 and are then flattened out on the rear side of the sheet, thus forming at once an axis for the rotation of the paddle-wheel, and a means for holding the paddle-wheel in place upon the sheet 10. The rack 45 is similar to the rack 20 except in this instance it is upside down and is positioned to engage directly projections 46, then the periphery of the paddle-wheel so that the paddle-wheel itself becomes the driving gear. The projections 46 when appearing upon the face of the toy are designed to appear as the blades of the paddle-wheel, but they are also shaped to serve as the gear teeth when they pass to the back of the main sheet.

The rack 45 is mounted for longitudinal movement by means of tabs 48 cut from the main sheet extending through slots 49 in the rack member as in the first embodiment.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having described our invention, what we claim as new and desire to secure by Letters Patent, is:

1. A mechanical element for animated toys comprising a card member having a hole therein serving as a bearing for a rotary member, a rotary card member having a plurality of radially extending tabs concentrically spaced about the axis of rotation and adapted to extend through said hole and serve as a journal therein, said card member having a circular periphery and teeth equally spaced around said periphery and extending outwardly therefrom, and a rack member slidably mounted on said card, constructed to engage said teeth.

2. A mechanical element for animated toys comprising a card member having a hole therein serving as a bearing for a rotary member, a rotary card member having a plurality of radially extending tabs concentrically spaced about the axis of rotation and adapted to extend through said hole and serve as a journal therein, said card member having a circular periphery and teeth equally spaced around said periphery and extending outwardly therefrom, and a rack member slidably mounted on said card, said rack member comprising a sheet of card board folded parallel to one edge to embrace the edge of said rotary member and having space holes along the fold through which the teeth extend.

3. A mechanical element for animated toys comprising a card member having a hole therein serving as a bearing for a rotary member, a rotary card member having a plurality of radially extending tabs concentrically spaced about the axis of rotation and adapted to extend through said hole and serve as a journal therein, said card member having a circular periphery and teeth equally spaced around said periphery and extending outwardly therefrom, and a rack member slidably mounted on said card, said rack member comprising a sheet of card board folded parallel to one edge to embrace the edge of said rotary member and having space holes along the fold through which the teeth extend, said card member and said rack member having sliding bearing comprising slits cut through one of said members parallel to the direction of motion and tabs cut from the other said member adapted to extend through said slits.

4. A mechanical element for animated toys comprising a card member having a hole therein serving as a bearing for a rotary member, a rotary card member comprising a front element having a plurality of radially extending tabs concentrically spaced about the axis of rotation and adapted to extend through said hole and serve as a journal therein, and a back member having slots to fit over said tabs on the other side of said card member, said back member having a circular periphery and teeth equally spaced around said periphery and extending outwardly therefrom, and a rack member mounted on said card in position to engage said teeth.

5. A mechanical element for animated toys comprising a card member having a hole therein serving as a bearing for a rotary member, a rotary card member comprising a front element having a plurality of radially extending tabs concentrically spaced about the axis of rotation and adapted to extend through said hole and serve as a journal therein, and a back member having slots to fit over said tabs on the other side of said card member, said back member having a circular periphery and teeth equally spaced around said periphery and extending outwardly therefrom, and a rack member comprising a sheet of card board folded parallel to one edge thereof to embrace the edge of said tooth bearing member, and having space holes along the fold through which the teeth extend, and means for mounting said rack member for motion parallel to said folded edge.

6. A mechanical element for animated toys comprising a card member having a hole therein serving as a bearing for a rotary member, a rotary card member comprising a front element having a plurality of radially extending tabs concentrically spaced about the axis of rotation and adapted to extend through said hole and serve as a journal therein, and a back member having slots to fit over said tabs on the other side of said card member, said back member having a circular periphery and teeth equally spaced around said periphery and extending outwardly therefrom, and a rack member comprising a sheet of card board folded parallel to one edge thereof to embrace the edge of said tooth bearing member, and having space holes along the fold through which the teeth extend, cooperating means upon said rack member and said card member to permit relative sliding motion parallel to said folded edge comprising slots in one of said members and tabs upon the other member extending through said slots.

7. An animation comprising a card member, a rotary member pivoted to rotate upon the face of the card and having a portion extending through said card having radially extending teeth, and a folded strip having openings in the fold to receive said teeth to serve as a rack, and means for slidably mounting said folded strip on the back of said card.

8. A card member having a rotary member pivoted to rotate upon the face of the card having a portion extending through a slit to the back of the card, said rotary member having radially extend-

ing teeth and a folded strip having openings in the fold to receive said teeth to serve as a rack, and means for slidably mounting said folded strip on the back of said card.

9. A card member having a rotary element thereon, radially extending teeth upon said element and a folded strip having openings in the fold to receive said teeth to serve as a rack, and means for slidably mounting said folded strip on the back of said card.
